UNITED STATES PATENT OFFICE

103,229

DESIGN FOR A CARTON OR SIMILAR ARTICLE

Max Haessler, Buenos Aires, Argentina

Application December 31, 1936, Serial No. 66,838

Term of patent 14 years

To all whom it may concern:

Be it known that I, Max Haessler, a citizen of the German Republic, residing at Buenos Aires, Argentine Republic, have invented a new, original, and ornamental Design for a Carton or Similar Article, of which the following is a specification, reference being had to the accompanying drawing forming part thereof.

Fig. 1 is a planar development of a carton or similar article showing my new design, and
Fig. 2 is a perspective view thereof assembled.

I claim:

The ornamental design for a carton or similar article as shown.

MAX HAESSLER.
